FLOYD CALVIN WEAVER, OF WASHINGTON, DISTRICT OF COLUMBIA.

GRINDING AND LAPING MACHINE.

1,422,505.

Specification of Letters Patent. Patented July 11, 1922.

Application filed November 11, 1920. Serial No. 423,371.

To all whom it may concern:

Be it known, that I, FLOYD C. WEAVER, a citizen of the United States, residing at Washington, in the District of Columbia, 5 have invented certain new and useful Improvements in a Grinding and Lapping Machine, of which the following is a specification, reference being had therein to the accompanying drawings.

10 This invention relates to a grinding and lapping machine and the object is the production of a machine for the making of precision true plane surfaces of glass or other crystalline materials.

15 Another object of the invention is the production of a machine for producing and finishing the precision true plane surfaces necessary for test of "gage blocks," both in the process of making and when they are 20 removed from the machine for use.

A still further object of the invention is the construction of a machine which is adapted for producing and finishing with optical surfaces the aforesaid "gage blocks."

25 It is to be understood that my machine will produce all practicable shapes or blocks with flat surfaces for the optical interference testing the diameters of bearing rollers, ball bearings, small cylinders, etc.; also, 30 the exact comparison of two similar diameters denoted by two corresponding flat surfaces.

A further object of the invention is the production of a machine whereby optical, 35 true, plane surfaces are produced, necessary for the most highly precise method of length comparison by light interference methods which are now universally established. In conjunction with the aforesaid means of 40 precise measuring, is the production of permanent standards of length in duplicate, adapted to the above method of test and also equally suitable for industrial snap gage checking, etc., as is required in precision tool and machine work, roller and ball 45 bearings, watch making, etc.

With these and other objects in view, my invention comprises certain novel combinations, constructions and arrangements of 50 parts as will be hereinafter described, illustrated in the accompanying drawings, and more particularly pointed out in the appended claims.

In the drawings:

55 Figure 1 is a top plan view of the polishing or lapping or grinding machine.

Figure 2 is a sectional view, taken on line 2-2, Fig. 1, and looking in the direction of the arrows.

Figure 3 is a sectional view, taken on line 3-3, Fig. 1, and looking in the direction of the arrows.

Figure 4 is a sectional view, taken on line 4-4, Fig. 1, and looking in the direction of the arrows.

Figure 5 is a transverse, sectional view showing the method of mounting the "gage blocks" in a circular disc form upon an optically flat surface, the "gage blocks" being separated by a hard wax or resin, or a 70 perforated metal plate 63 bedded in the hard wax for holding blocks in addition to the resin, and the outside supported by a brass or metallic retaining band fitting tightly to the flat supporting surface and being of a 75 height slightly less than the "gage block." This mounting of the "gage blocks," with resin in the retaining ring, or also a metal 80 perforated spacing plate added, all fitting tightly upon the optical flat surface, are shown held rigidly in position by wedges between the outer ring fastened securely to the plate mounted on the driving spindle. Also this outer ring secures the position of the optical flat surface by wedges, as shown. 85

Figure 6 is a vertical section of the circular blocking arrangement for glass and crystalline materials. The faces of discs to be worked are turned downward upon a master flat surface, the discs being set into 90 recesses cut in a disc of similar glass of the same thickness and the tops of the intervening spaces closed by paraffin to be watertight. An outer stiff retaining metal band is set upon a ring, forming an open topped 95 vessel on the master flat surface into which plaster Paris is poured over top of discs. Over the discs set into the recessed plate is set a second plate of glass of same thickness as the discs and at a distance above them 100 equal to at least one quarter their thickness and parallel to the same, and of a diameter not less than that of the recessed disc. A stiff, webbed, thin metal plate with recess for driving pin is set into top of block 105 before the "plaster of Paris" sets hard forming a rigid block. When plaster has hardened the flat ring is removed and plaster trimmed away in relief from recessed plate, also the remaining space between the discs 110 and the recessed plate is filled with beeswax, thus forming a rigid block which is then

worked in one of two ways upon the lapping machine. First where the block is worked over the top of a master flat lapping disc and second when mounted on the 5 spindle plate in identical manner to the "gage block" mount as shown in Fig. 5.

Figure 7 shows the method of precise optical interference tests, first by circular fringe or plate parallel surface test between 10 a top transparent flat and a projecting portion of the master flat surface upon which the gages are mounted, second the parallel fringe method using a top transparent flat for testing flatness of individual blocks or 15 glass discs and also the agreement of "gage blocks" with a standard block which is set upon projecting edge of the master flat surface. This latter method is for duplication of standard gages, in process of working; 20 the parallel fringe method is used when "gage blocks" are still much too long i. e. 0.002 millimeter or .0001 inch and less, and the circular fringe or optical plane parallel test when the differences between "gage 25 block" and the standard block are in the order of .0005 millimeter or .00002 inch down to .000001 inch. It is pointed out that when convenient the wedges are removed from the outer ring to give a clear 30 space for the optical testing against the projecting edge of the master flat surface.

Referring to the drawings by numerals, 5 in Fig. 1 is the sole power drive to the lapping machine, belt or direct connected 35 motor, etc. In Figs. 1, 2, 3 and 4, power drive 5 is positively connected by gearing or chain belt to both vertical spindles carrying plates 6 and 9. Plates 6 and 9 are thereby driven in a fixed relation to each other and 40 are so constantly maintained in that relative rotation. Plate 6 and plate 9 each carry vertical bearing posts 7 and 10, respectively, which are capable of adjustment in such manner as shown by T slot 11 of plate 9, so 45 as to have adjustment of stroke or throw when plates 6 and 9 revolve about their fixed vertical axes, which bearings are made rigid with machine body. Plate 9 is shown in sections 2-2 Fig. 2 and 4-4 Fig. 4 to be 50 capable of adjustment position of throw of post 10 relative to that of post 7. Plate 9 is shown in section 2-2 Fig. 2 to rest upon machined plate 35 which is rigidly fastened to the vertical spindle 38. Thus plate 9 can 55 be set by index marks at section 4-4 and when desired setting is made, plate 9 is firmly clamped in fixed relation by screws 58 to plate 35.

The lapping plate 27 is thus driven by 60 the tool pin 26 actuated by posts 7 and 10 connected to 26 by thrust bars 14 and 18, respectively, with a flexible joint 16. Thrust bars 14 and 18 join posts 7 and 10, respectively, with hinge joints as shown at post 65 10, also length of both bars 14 and 18 are

adjustable by locking double screw turn-buckles or telescoping slides with clamping screws 15 and 17, respectively. The tool pin 26 is thereby adjustable in stroke from practically a straight line to a circle, with intermediate elliptical strokes of the entire range of eccentricities. Thus the strokes of tool pin 26 actuate the lapping plate 27 over the work (as blocks 28) mounted on plate 30. The amount of lapping of lapping plate 27 70 can be distributed in any manner desired over work mounted on plate 30 by both adjusting strokes of tool pin 26 and by rotating plate 30 about its vertical axis 42 mounted in rigid bearings of the machine 75 frame. Pressure on lap 27 is obtained by adding cylindrical weights 59 on tool pin 26.

Plate 30 is driven positively by gearing, or chain belt, through a friction clutch 20 from shaft 12 by bevel gears 13 on shaft 12 80 and 33 on shaft 19. Shaft 19 is thereby capable of driving plate 30 through bevel gears 22 and 41 or to be independent and locked in position by friction clutch 20. Also plate 30 can be actuated by hand 85 wheel 24 through shaft 23 and bevel gears 34 and 21. Gear 21 is provided with a clutch so that when clutch 20 is disengaged, gear 21 is then engaged to drive bevel gear 22 and 41 and plate 30. Thus it is shown 90 how plate 30 may be driven automatically through clutch 20, and also by disengaging 20 and engaging clutch on bevel gear 21, plate 30 is then driven by hand wheel 24.

The following adjustments are special to 100 this machine, first, adjustment of length of strokes or throw of posts 7 and 10 of driving plates 6 and 9, respectively by T slot 11; second, adjustment of relative position of post 10 on plate 9 with respect to position of 105 post 7 on plate 6 by means of a plate 35 and clamping screws 58, shown in Fig. 2; third, adjustment of the length of bars 14 and 18 by turn-buckles or sleeves 15 and 17, respectively, so provided with locking nuts 110 that position of strokes of tool pin 26 may be altered or changed at will of operator, thereby placing the effect of lap 27 to any zone or sector of work mounted on plate 30; fourth, adjustment of the drive of plate 30 115 by means of clutch 20 to be automatic and by clutch on gear 22 to be hand-controlled in order to effect concentration of lapping to particular zones or sectors, respectively, on the work.

Certain features of this machine of importance are; plane disc laps or grinding tool 27 and master flat plates 43 as can be readily turned and surface ground; the machine laps and finishes its own plates, as 125 well as using these same laps, in producing optical flats, etc., and "gage blocks;" and the machine gives an optical polish to both metal and glass surfaces which gives full use of the optical tests; the most precise optical 130

tests are applied to work on the machine without removal or alteration; local finishing and retouching is done as delicately and effectively by the machine as is accomplished by expert hand workers.

The method of "blocking" or of mechanically holding the "gage blocks" 28, is shown in Fig. 5. These blocks 28 are set firmly upon the top surface of master flat surface 43 and in intimate contact. This process of setting (sometimes called "ringing") is facilitated in case of transparent blocks where setting by black fringe indicates the closest contact to master surface. Blocks 28 are first prepared by preliminary grinding and machining to have general dimensions of final block, with small excess stock to facilitate the final precision lapping. This also applies to metallic and glass or crystalline blocks as well. Blocks 28 are placed in contact with master flat surface 43 in uniform or symmetrical arrangement inside the brass ring 29, and with a small space between each block 28. Ring 29 fits accurately upon top surface of 43 and is slightly less in height than finished length of blocks 28. Blocks 28 when arranged on 43 are held firmly in position by the heavy lapping tool 26 placed upon them. Ring 29 is held concentric with 43 by means of wedges 45 bearing against the plate ring 44. This plate ring 44 is in turn wedged concentric and firmly to the main spindle plate 30. Plate 30, Fig. 5, is a plane lapped plate and turned and finished cylindrical edge and is rigidly fastened to the vertical spindle 42 of Fig. 3. Ring 44 has a shoulder bearing on top of 30 as well as on the outer cylindrical edge of 30 and with a small amount of clearance. Thus it is seen that 44 is then held firmly and rigidly on 30 by wedges 59. The master flat surface 43 with one flat lapped surface in contact with the top lapped surface of 30 is held rigidly by wedges 46 concentric with 44, and also with 30. Thus the entire mount is held rigidly in concentric position ready for lapping, etc., and also capable of being entirely dismantled, cleaned, etc., and returned precisely to its original condition and adjustment. With blocks 28 so mounted upon master surface 43 as above described, the intervening space between blocks is poured full of melted hard wax, resin or compounds of resin and shellac, etc., as indicated by a spout 47 at points around the space between ring 29 and the lap 27 which prevents blocks 28 from lifting away from master surface 43 or changing from placed positions. Wax 60 is not filled into spaces between blocks and ring higher than brass ring 29. When wax 60 hardens, lap 27 is removed until lapping operation is started when the lap 27 is returned to position as shown in Fig.

5 and tool pin 26 put into hole as shown 65 ready for driving. Thus, the master surface 43 is mounted such that its own weight produces no distortion and its means of clamping by wedges 46 produces no deflection within absolute methods of testing of 70 top surface. Also, when master surface 43 is made of glass, etc., a thin non-heat-conducting layer is placed between it and plate 30, and plaster Paris cast into groove otherwise occupied by wedges 46 and substituted 75 for them.

Optical interference tests with master plates readily determine the flatness of 43 and also tops of blocks 28. During progress of lapping, as will be hereinafter fully described, blocks 28 can be compared by optical interference test against outer projection surface of 43 beyond ring 29 for uniformity of height or agreement with a given standard block, or for flatness of top surface, and also lapping plate 27 can be frequently tested in like manner for flatness of surface. Wedges 45 are removed when making optical interference tests to master surface 43; however, it is found in practice that necessary wedges 45 occupy a very small part of the circular zone of 43 and it is seldom necessary to remove them at all. Ring 44 has the two inner surfaces bearing against wedges slightly conical to facilitate the wedging 95 action of 45 and 46. Outside of 44 is made smooth and free of burrs and projection portions to facilitate cleaning; also, to enable operator in last stages to give smoothness to hand operation of plate 30 by using hand 100 in addition as a delicate brake on rim 44. One end of "gage blocks" 28 is first lapped as above described for a flat surface and polished; second, the first finished surface of 28 is set on 43 similarly to operation for first 105 surface and the second surface is then lapped for flatness and for parallelism. The check for parallelism and for given thickness or "separation" of two parallel surfaces of 28 will be described in treating of Fig. 7. The 110 lapping plate 27 for metallic bodies 28 has thick metal discs reinforced by webs and a rim at back and a hub with recess for ball of tool pin 26. The lapping surface is carefully turned, also edges, and ground and 115 lapped to an optical plane surface. This surface of 27 is grooved for large blocks 28 and left smooth for small blocks 28. Small holes 61 in lap 27 feed the lapping abrasive to under lapping surface from the recess on 120 back of 27 formed by the hub, webs and rim. Lap 27 is also used in lapping master surface 43 as well as plate 30 when setting up the machine. The lapping plate 27 for glass, etc., is changed to a form described by Fig. 125 6, where the physical characteristics of glass, etc., require fundamentally different consideration and treatment, however the same

processes of working and lapping apply throughout after the blocking is accomplished.

- It is to be noted that ring 29 and ring 44 are provided with divisions and designating marks on outside rim every ninety degrees, also on outer cylindrical edge of master surface 43. This enables and facilitates repeating relative settings and particularly in recording and operating on particular zones and sectors of blocked work on surface 43, as is necessary in lapping parallel surfaces and in removing geometrical errors from flat surfaces.
- 15 In the final lapping or finishing, an optical polish is given blocks 28 by coating the surface of lap 27 with a compound of pitch, resin, beeswax and rouge in a layer about one quarter of an inch in thickness; and the 20 polishing operation is then carried out precisely as the previous lapping operations. The lap is fed with more rouge mixed in lime water and soda through the small holes 61 in the lap 27.
- 25 Fig. 6 shows the method and process of blocking glass and crystalline materials for precision flat surfacing. Also, the fundamental starting point as for metallic lapping is the master flat surface 43. In most 30 refined working of glass, the master surface 43 is made of annealed glass, while for working metallic bodies master surface 43 is made of metal and optically polished. In blocking discs of glass 55 for making 35 glass master surfaces, they are set with the face to be worked against master surface 43 with a very small amount of volatile oil, naphthalene, benzine, etc., and set in recesses cut in a larger disc 54 of similar glass of the 40 same or greater thickness, preferably the same thickness, also set against surface 43 in a similar manner to 55. Discs 55 are set concentric with the slightly larger recesses cut in 54. Concentric with 54 is set 45 the auxiliary blocking ring 48 against surface 43. Upon this ring 48, which is carefully machined, is set the metal binding ring band 49 fitting tightly to top of ring 48 so as to hold the liquid plaster Paris when casting. With blocks or discs 55 placed with 54 on surface 43 and with band 49 on ring 48 the top edges of space between discs 55 and recess in 54 are painted with a brush and melted paraffin or beeswax as 62 so as 55 to prevent plaster Paris mix from flowing down into recess. Also great care is to be exercised in keeping the paraffin or beeswax from entering down appreciably into this space. The outside edge of disc 54 is also 60 lightly painted with paraffin or beeswax to prevent plaster Paris mix from entering between surfaces of 54 and 43. The plaster Paris is then poured into the block until it covers top of 54 and 55 by approximately 65 one half their thickness. The plate 50 of

similar glass of at least the same thickness of 54 and 55 and of a diameter slightly larger than 54, is set above the plates 54 and 55 parallel to them and at a separation of not over one half their thickness before the 70 plaster Paris begins to set. Disc 50 is painted with a thick paraffin coat about one sixteenth of an inch on only the outer cylindrical portion of the disc before setting into the plaster. Also disc 54 is previously 75 treated likewise on outer cylindrical surface and then set on master surface 43. The plaster Paris is allowed to harden and dry just coming to the top edge of disc 50 but not on top face of disc. The edge of 80 plaster Paris between disc 50 and band 49 is then painted with paraffin to be water tight and sealed. The second pouring of plaster Paris is now made being just enough to completely fill remaining space when top 85 blocking plate 51 is pressed down flush with the top edge of band 49. Plate 51 is a thin metal, preferably, aluminum, plate stiffly ribbed at back and edge with a circular recess for the hard wooden block 52, which 90 carries tool point. The bottom face 51, as well as the outer cylindrical edge, is accurately turned, also, top edge of rim to be parallel to bottom face and the edges of center recess to be in same plane as rim edge. 95 This enables the plate 51 being set in plaster accurately and concentrically by wedges and by placing a heavy lapping tool with flat face bearing down on top rim edge of 51 causing the plate to sink in plaster until 100 face of lapping tool rests upon the top edge of band 49. In this position, the plaster is allowed to harden and dry, when plaster is hardened and dry lapping tool is removed and exposed ring of plaster sealed water tight 105 with paraffin. The entire block is now removed from master surface 43 and ring 48 is also removed by light tapping downward away from band 49. The plaster ring between 54 and 49 is trimmed to relieve away 110 from 54, i. e., as relieving type, about one sixteenth inch below the edge of 54 formerly in contact with 43. This ring of plaster, when so relieved, is impregnated with melted paraffin to be water tight. The 115 remaining spaces between discs 55 and walls of the recesses in 54 are filled with melted beeswax or resin. This gives the edge support to discs 55. When disc 54 is left one solid glass disc, it is made up and used 120 as a master surface in place of 43 and set up in an identical manner for the most refined glass flat and plane parallel working as hereinbefore described metallic "gage blocks" 28. Glass plane parallels similar to blocks 28 are worked in precisely the same manner, the lap 27 becomes the solid disc of glass blocked as described, Fig. 6, and the master surface 43 is replaced by a second solid disc of glass blocked as in Fig. 6, and 125 130

upon which the glass bodies are treated as described for metallic bodies 28. In case of plane surface bodies as 55 above described method of blocking Fig. 6, the finished block 5 in band 49 is turned glass side up on plate 30 and treated as master plate 43 when being lapped by a tool 27, only in last stages a glass lap is used in place of metal one. The process and method of blocking glass 10 discs described as shown in Fig. 6 gives a glass lap or master surface 43 which functions as described above for working glass bodies 28, gives the means of lapping the testing flat surfaces as are required in process 15 for working both metallic and glass bodies 28, i. e. "gage blocks" and "optical plane parallels" as will be described for Fig. 7, also for the auxiliary tests of blocks 28 removed from machine. It is also pointed out that 20 these glass flat surfaces are fundamental in all precision optical equipment testing, etc., hence a field of application quite as wide as its applications to metallic gages, etc., and quite removed including practically every 25 scientific field of endeavor as well.

The specific points of claim for the process of blocking Fig. 6 is; first, a method of casting or setting a disc of glass, etc., in plaster block without mechanical compression and deflection stresses; second, a method 30 of setting the discs 55 and 54 to have a flow of heat upon temperature change in a direction normal to precision flat surface by employment of a buffer and insulator barrier 35 disc 50 in Fig. 6 for heat coming to or away from 54 and 55, the action being in a sense that of insulation and also that of an equalizer, the paraffin at edges of discs 50, 54 and 55, acting as heat insulator with the 40 ring of dry plaster Paris and also relieving the compression of the plaster Paris on edge of discs; third, that by the method of blocking, Fig. 6, using a lapping disc so blocked in place of 27 and the discs 54 and 55 or one 45 solid disc as 54 and for plane surface working as 43 or for plane parallels of glass, etc., the effect of the heat produced in the lapping and polishing process and that which may come from external room 50 sources will be to cause only geometric errors due to heat expansion. These errors are chiefly the surfaces changing from one very long radius of curvature to a longer or shorter radius, and these errors are directly 55 measured and interpreted by interference testing with a master optical flat surface, enabling a direct adjustment of lapping effort on the machine i. e., stroke of tool pin 26 and rotation of plate 30 to reduce the errors 60 of the surface within the range of the oscillating heat and expansion changes found for a given disc form for a given temperature. It is also stated that different disc forms, i. e., discs of the same diameter but of different 65 thickness behave far out from any ratio

of their dimensions when the flatness of surfaces or the flatness and the parallelism of its two surfaces are considered under the effect of temperature changes and with the methods of applying heat or drawing heat 70 away to another mass or body.

In Fig. 7 is shown the method of optical interference testing upon the "gage blocks" 28 in process of working. It is to be noted that the application of test by optical flat 75 discs 56 is very readily and quickly applied. The lap 27 being removed and the top surface of blocks 28 cleaned, also the edge of 43 projecting beyond the band 29 is thoroughly cleaned. The complete test of work 80 in progress is then as follows. First, a test of flatness of blocks 28 by placing optical flat 56 upon 28 and gently pressing downward until intimate contact is obtained showing for flat surfaces of 28, alternate straight 85 bright and dark lines parallel to each other and equally spaced. Second, the test for parallelism of top and bottom surfaces of blocks 28, by placing 56 upon top of 28 and letting one edge project over such that 90 outer part of surface of 43 can be seen along A—A through projecting portion of 56, so that if 56 is pressed firmly on 28 until contact is so intimate that no interference 95 bands are seen then upon sending monochromatic light in the direction of A—A toward surface of 43, a transparent glass at M will transmit light along A—A also reflect the circular fringe system shown above of alternate light and dark rings produced between 100 surface of 56 and 43 and seen at E or with light source at E system is viewed along A—A, so upon moving position at E keeping M fixed in adjustment parallel surfaces upon 28 will be indicated by this system of rings 105 remaining unchanged, if blocks 28 are not parallel surfaced the ring system will change and when a distance α has been traversed with two new centers appearing to the ring system a difference of separation of the two 110 surfaces of 28 has been encountered, i. e., approximately .000050 m. m. or .00002 inch, hence, if α is known the angle of wedge of surfaces is at once known. This test is carried around the entire surface of 43 and 115 band 29 and the position of highest and lowest blocks noted for further lapping. Third, the test for agreement to a given standard block, 57 is made with an optical flat 56 placed carefully in as intimate contact 120 as possible with at least two blocks 28 and the standard block 57 in such a manner that a portion of outer free surface is included between the blocks and then the plane parallel test is applied as above described using 125 the circular fringe system, the interference occurring between 43 and lower surface of optical flat 56, i. e., along line B—B. The angle of wedge above described always indicates the higher or longer block, i. e., 28 130

or 57, and how much the length must be reduced. This method of working, above described, gives a direct measure of the errors numerically and by timing the rate of lapping for the condition of working maintained constant, the error is readily reduced to the limits of measurement and the intrinsic physical characteristics of the blocks 28 and 57 and the optical flat 56.

- 10 Practice shows that the optical flats 56 need not be larger than one half the diameter of band 29, as the larger flats have temperature characteristics that outbalance unfavorably the convenience of covering a large area possesses for the general routine of the process. Also it is well to have band 29 not over three fourths the diameter of 43, and it is more advantageous to have 29 two thirds the diameter of 43.
- 15 20 It is pointed out that for "gage blocks" 28 made of glass, i. e., plane parallels, the tests are more direct and simple since the media of block is transparent and the plane parallel test is directly applied. The agreement test to a standard block 57 however is carried out in precisely the same manner as above described for metallic blocks 28.

While I have described the preferred embodiments of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In a machine of the class described, the combination of a pair of plates, means for rotating said plates at the same rate of speed, a work-supporting plate contiguous to said pair of plates, means for driving said work-supporting plate at the same speed the first-mentioned plates are driven, a lapping plate contiguous to said work-supporting plate, means connecting one of the first-mentioned plates to said lapping plate for moving the lapping plate over the work-supporting plate, and means adjustably connecting said just-mentioned connecting means to the other plate of the pair, whereby movement of the lapping plate with reference to the work-supporting plate will be controlled through the medium of said first-mentioned plate.

2. In a machine of the class described, the combination of a pair of plates, means rotating said plates at the same speed, a work-supporting plate, means rotating said work-supporting plate at the same speed as the first-mentioned plates, a lapping plate over said work-supporting plate, and means connecting said lapping plate to both of said first-mentioned plates for moving the lap-

ping plate over the work-supporting plate when the first-mentioned plates are rotated.

3. In a machine of the class described, the combination of a pair of simultaneously driven plates, a work-supporting plate moving in time relation to said first-mentioned plates, a lapping plate adapted to move with relation to one face of the work-supporting plate, and means connecting said lapping plate to both of the first-mentioned plates of the pair, whereby the movement of the lapping plate with reference to the work-supporting plate is controlled at two points of the machine.

4. In a machine of the class described, the combination of a plurality of plates including a work-supporting plate all rotating at a fixed speed, a lapping plate adapted to move with respect to one face of the work-supporting plate, means for stopping the movement of the work-supporting plate while the other plates are moving in time relation, and manually-operated means for moving the work-supporting plate while the other plates are in continuous movement independent of said manually-operated means.

5. In a machine of the class described, the combination of a plurality of plates including a work-supporting plate, means for driving all of said plates at the same speed, a lapping plate over said work-supporting plate, means connecting the lapping plate with one of the first-mentioned plates for causing the lapping plate to move when movement is imparted to the connected plate, and means adjustably connecting the lapping plate to another of the plates for controlling the movement of the lapping plate with respect to the work-supporting plate.

6. In a machine of the class described, the combination of a series of plates including a work-supporting plate rotated at the same speed, a lapping plate over said work-supporting plate and moved or driven with respect to the work-supporting plate by two of the first-mentioned plates, means for causing the work-supporting plate to remain idle independent of the movement of the other plates, and means for manually moving or driving the work-supporting plate at a speed different from the speed of movement of the other plates.

7. In a machine of the class described, the combination of a pair of spaced plates, a work supporting plate, means for driving all of said plates at a uniform rate of speed, a lapping plate over said work supporting plate, and adjustable means connected to said first-mentioned pair of plates and to said lapping plate for moving said lapping plate in a stroke that ranges from a circle to a straight line, as may be desired, as and for the purposes set forth.

8. In a machine of the class described,

the combination of a pair of spaced plates, a work supporting plate, means for driving all of said plates at a uniform rate of speed, a lapping plate over said work supporting plate, an adjustable bar connected to one of said first-mentioned pair of plates and to said lapping plate, and an adjustable bar connected to the other first-mentioned plate and to said first-mentioned bar, as and for 10 the purposes set forth.

9. In a machine of the class described, the combination of a pair of spaced plates, a work supporting plate, means for driving all of said plates at a uniform rate of speed, 15 a lapping plate over said work supporting plate, a post eccentrically mounted upon one of said first-mentioned pair of plates, the remaining plate of the pair being provided with a slot extending across its top surface, 20 a post adjustably mounted within said slot, a post mounted upon said lapping plate, an adjustable bar mounted upon said first and last mentioned posts, and an adjustable bar connected to said second-mentioned post and 25 to said first-mentioned bar, as and for the purposes set forth.

10. In a machine of the class described, the combination of a pair of plates, spindles supporting said plates, bevel gears mounted upon said spindles, a shaft having bevel 30 gears at its ends engaging said first-mentioned bevel gears, a bevel gear on said shaft intermediate its ends, a power driven means for rotating one of said first-mentioned bevel gears, whereby rotary motion is im- 35 parted to both of said plates, a work supporting plate, a spindle supporting said work supporting plate, a bevel gear on said last mentioned spindle, a second shaft having bevel gears on its ends engaging the 40 bevel gear on said last-mentioned spindle and the remaining bevel gear on the first-mentioned shaft, a clutch on said second-mentioned shaft, a manually operated drive means connected to the second-mentioned 45 shaft, a lapping plate over said work supporting plate, and means connecting said first-mentioned plates to said lapping plate, as and for the purposes set forth.

In testimony whereof I hereunto affix my 50 signature.

FLOYD CALVIN WEAVER.
